UNITED STATES PATENT OFFICE

2,041,219

METHOD OF DESTROYING MOTH LIFE

Marion E. Wade, Chicago, Ill., assignor to Moth King Corporation, Chicago, Ill., a corporation of Illinois

Application April 13, 1935, Serial No. 16,111

4 Claims. (Cl. 21—18)

The present invention has reference to the destruction and devitalization of moths and the eggs, larvæ and pupae of moths, that is, all stages or forms of moth life, and the primary object thereof is to provide a method of ridding garments, rugs, bedding, furs and other articles of adult moths and other stages of moth life which is more efficacious than previously proposed methods and comprises as the main steps thereof, 10 first, placing the articles to be treated in a comparatively small space, such for example as a closet, then rendering the closet airtight by applying strips of adhesive tape or similar sealing material around the edges of the door for the 15 closet, and finally after the sealing operation, heating within the closet substantially pure or unadulterated orthodichlorobenzene until a sufficient amount has been vaporized to form a gas which completely fills the space within the closet 20 and is of such potency that it destroys and devitalizes all stages or forms of moth life in the articles and closet.

Another object of the invention is to provide a method of destroying or devitalizing moth life 25 which may be carried out not only in a simple manner and expeditiously, but also cheaply.

Other objects of the invention and the various advantages and characteristics of the present moth destroying method will be apparent from a 30 consideration of the following detailed description.

The invention consists in the several novel features which are hereinafter set forth and are more particularly defined by claims at the conclusion hereof.

35 In the drawing which accompanies and forms a part of this specification or disclosure and in which like numerals of reference denote corresponding parts throughout the several views:

Figure 1 is a fragmentary perspective of a closet 40 having on the top shelf thereof a device which is designed for use in carrying out the improved method and consists of a container for the orthodichlorobenzene and an electric heater for heating the container to vaporize the orthodichlorobenzene;

Figure 2 is a vertical section of the device illustrating in detail the construction of the container and the electric heater;

50 Figure 3 is a fragmentary inverted plan of the device showing the arrangement and construction of the resistance element which forms the heating means for the heater;

Figure 4 is an enlarged, vertical section of the 55 heater of the device illustrating the manner in

which the resistance element is secured in place; and

Figure 5 is a detail section showing the manner in which the cracks along the edges of the door of the closet of Figure 1 are sealed by adhesive tape in order to render the closet air-tight prior to vaporizing orthodichlorobenzene therein in carrying out the improved method.

The method which forms the subject matter of the invention contemplates the vaporization of orthodichlorobenzene for the purpose of destroying and devitalizing moths and the eggs, larvæ and pupae of moths, and is adapted to be carried out by way of the device shown in the drawing. This device consists of a container 6 for the orthodichlorobenzene and an electric heater 7 for the container, and is adapted as hereinafter described and in carrying out the improved method, to be placed in a sealed compartment such as a closet C containing garments, rugs, bedding, furs and other articles which are subject to attack by moth larvæ.

The container 6 is in the form of a sheet metal can and comprises a cylindrical side wall 8, a circular bottom 9 and a circular top 10. The bottom 9 embodies an annular foot 11 at the margin thereof and this foot serves to support the container 6 when the latter is placed on a flat surface. The top 10 of the container has an integral, centrally located, externally threaded neck 12 which is normally closed by an internally threaded cap 13. The container is adapted to be filled with orthodichlorobenzene which when vaporized in the manner hereinafter referred to forms a moth-destroying gas.

35 The electric heater 7 is adapted to support the container 6. It serves when operated to vaporize the orthodichlorobenzene in the container and consists of a sheet metal casing 14 and a heating element 15. The casing 14 is supported by a plurality of legs 16 and comprises a circular top 17, a side wall 18, and a bottom 19 which together form a compartment 20 for the heating element 15. The upper portion of the side wall 18, as shown in Figures 2 and 4 of the drawing, extends 40 downwardly and then outwardly and forms an annular seat 21 in which fits removably the bottom 19. The legs 16 are formed of fiber or like material having low heat conducting characteristics and are in the form of disks. The upper 45 portions of the legs fit against the inner face of the bottom portion of the side wall 18 and are secured in place by bolts 22. The bottom 19 is circular and rests on the upper portions of the legs 16. The top 17 is the same in diameter as the 50

bottom 9 of the container 6 and is adapted to engage and support the latter when the container 6 is placed upon the heater 7 for heating purposes. When the container 6 is placed or mounted on the heater the annular foot 11 fits snugly around the extreme upper portion of the side wall 18 of the casing 14 and holds the container against lateral displacement with respect to the heater casing.

10 The heating element 15 is in the form of a strip or length of nichrome wire and is wound around a rectangular piece 23 of mica or like insulating material. This piece 23 is disposed between a mica disk 24 directly under the top 17 of the heater casing 14 and a rectangular mica piece 25 on a plate 26 in the upper portion of the compartment 20. The plate 26, as shown in the drawing, is suspended from the casing top 17 by means of a pair of diametrically opposite rivets 27, and serves to clamp the mica disk 24 and the mica piece 25 against the heating element 15 and to hold them in place. Current is supplied to the element 15 by means of a cord 28 which comprises a pair of conductors 29. One end of this cord extends through a hole 30 in the central portion of the casing bottom 19 and the other end is provided with a plug 31 whereby the cord may be connected to a wall socket for current receiving purposes. The ends of the conductors 29 which extend into the compartment 20 in the casing 14 lead through tubular posts 32 in the plate 26 and are connected respectively to the ends of the heating element 15.

35 The heating element 15 is of such capacity and is so designed and constructed with respect to the casing 14 that the heater 7, when the container 6 is placed thereon heats the orthodichlorobenzene in the container at a temperature ranging between 290° F. and 310° F. In practice it has been found that in order to obtain maximum efficiency it is essential that the orthodichlorobenzene be heated at a temperature within the aforementioned range inasmuch as the rate of vaporization of orthodichlorobenzene is a maximum within this range and the gas resulting from vaporization quickly fills the closet in which the method is carried out and is of such potency or concentration that it effectively kills all forms of moth life within the closet.

50 In using the device in the closet C to destroy and devitalize adult moths and the eggs, larvae and pupae of moths and thus to moth-proof garments, rugs, bedding, furs and all other articles which are disposed in the closet and are subject to attack by moth larvae, the electric heater 7 is first placed on the top shelf in the closet C. Thereafter the cap 13 is removed from the externally threaded neck 12 on the top 10 of the container 6 and the container is placed on the top 60 of the heater casing 14 so that the bottom 9 engages the top 17 of the casing 14. After placing the container with orthodichlorobenzene therein on the electric heater, the cord 28 is passed through the doorway of the closet and the door 65 for the closet is closed, as shown in Figure 1. The cord is preferably passed through the doorway of the closet so that it extends under one corner of the door and hence is not injured when the door is closed. After the door of the closet is closed, the closet is sealed by applying around the edges of the door, strips 33 of adhesive tape or similar sealing material. These strips are preferably coated on the outer faces thereof with any suitable material to make them non-porous, 70 and have a permanently pressure-sensitive ad-

hesive on their inner faces in order that they may be stuck in place along the door edges as shown particularly in Figure 5 of the drawing. If the closet door has a keyhole a small strip of adhesive tape is placed over the hole in order completely to seal the closet. After completely sealing the closet, the plug 31 on the free end of the cord 28 is inserted into the wall socket nearest the closet. When the container becomes heated to a temperature between 290° and 310° Fahrenheit the orthodichlorobenzene in the container 6 vaporizes at such a rate that the gas resulting from vaporization passes out through the neck 12 in the container top 10 and fills the closet C. The device is placed on the top shelf of the closet 10 for the reason that the gas resulting from vaporization of the orthodichlorobenzene in the container is heavier than air and hence the closet is best filled with the gas by so locating the device. The gas generated by the device penetrates all 15 of the articles in the closet and flows into all cracks and crevices in the closet so that all forms or stages of moth life within the closet are encountered by it. A sufficient quantity of the orthodichlorobenzene is vaporized so that the gas 20 is of such concentration or potency that moth eggs are devitalized and adult moths and all moth larvae and pupae are destroyed. In order to obtain the best results, at least one cubic centimeter of orthodichlorobenzene is vaporized for each 25 cubic foot of space in the closet. In a container having a diameter of approximately four (4) inches the rate of vaporization of orthodichlorobenzene is about sixty-five (65) cubic centimeters per hour provided that the container is heated 30 to a temperature between 290 and 310° Fahrenheit. If, therefore, there are one hundred and thirty (130) cubic feet of space in the closet and a container of the aforementioned diameter is used in connection with the electric heater 7, the heater is operated for two hours. After the proper amount of orthodichlorobenzene has been generated into gas within the closet, the plug 31 40 is removed from the wall socket so as to shut off the heater. The closet is then left in its sealed 45 condition for no less than 24 hours in order to effect the desired results as far as moth-proofing is concerned. After the closet has remained sealed for at least 24 hours and preferably 48 hours, the strips 33 of adhesive tape are removed from the 50 edges of the closet door, and the closet together with the articles therein is in a moth-proofed condition. Inasmuch as the gas resulting from the vaporization of orthodichlorobenzene in the container 6 completely fills the space within the 55 closet all moths or moth life in cracks or crevices in the closet or behind panels, footboards or moldings are destroyed.

The herein described method of moth-proofing articles is extremely simple and may be carried out 60 at a low cost because of the cheapness of orthodichlorobenzene.

The invention is not to be understood as restricted to the details set forth, since these may be modified within the scope of the appended 65 claims, without departing from the spirit and scope of the invention.

This application for Letters Patent is a continuation in part of my application Serial No. 722,629, filed April 27, 1934.

Having thus described the invention, what I claim as new and desire to secure by Letters Patent is:

1. That improvement in moth-proofing articles subject to attack by moth larvae which comprises 75

placing the articles in a closet or like small closed space, and then while the closet is closed vaporizing within the closet by way of heating at a temperature no higher than 310° F. at least one cubic centimeter of pure or unadulterated orthodichlorobenzene for each cubic foot of space within the closet in order to produce a gas which completely fills the closet and is of such concentration or potency as to destroy or devitalize all stages of moth life in the articles and closet.

5 2. That improvement in moth-proofing articles subject to attack by moth larvae which comprises placing the articles in a closet or like small closed space, and then while the closet is closed 15 vaporizing within the upper portion of the closet and at a temperature ranging between 290° and 310° Fahrenheit no less than one cubic centimeter of pure or unadulterated orthodichlorobenzene for each cubic foot of space within the closet 20 in order to produce a gas which completely fills the closet and is of such concentration or potency as to destroy or devitalize all stages of moth life in the articles and closet.

25 3. That improvement in moth-proofing articles subject to attack by moth larvae which comprises placing the articles in a closet or like comparatively small closed space, then sealing the closet by applying strips of sealing material along 30 the edges of the door and across all other openings leading to the closet, then vaporizing within

the sealed closet and at a vaporizing temperature, at least one cubic centimeter of pure or unadulterated orthodichlorobenzene for each cubic foot of space within the closet in order to produce a gas which completely fills the closet 5 and is of such concentration or potency as to destroy or devitalize all stages of moth life in the articles and closet, and finally after no less than twenty-four hours removing the sealing material and opening the door of the closet to 10 permit of the discharge of the gas therefrom.

4. That improvement in moth-proofing articles subject to attack by moth larvae which comprises placing the articles in a closet or like small space, then sealing the closet by applying strips of sealing material along the edges of the door and across all other openings leading to the closet, then while the closet is sealed, vaporizing in the upper portion of the closet by way of heating at a temperature ranging between 290° and 310° 20 Fahrenheit at least one cubic centimeter of pure or unadulterated orthodichlorobenzene for each cubic foot of space within the closet in order to produce a gas which completely fills the closet and is of such concentration or potency as to 25 destroy or devitalize all stages of moth life in the articles and closet, and finally after no less than 24 hours removing the sealing material and opening the door of the closet to permit of the discharge of gas therefrom.

30 MARION E. WADE.
